[57] CLAIM

The ornamental design for a shade holder, substantially as shown and described.

DESCRIPTION

FIG. 1 is a top perspective view of a shade holder showing my new design;

FIG. 2 is a front elevational view thereof;

FIG. 3 is a side elevational view thereof;

FIG. 4 is a bottom plan view thereof, and

FIG. 5 is a perspective view of the shade holder on a reduced scale, the fan and lighting fixture being shown in broken lines for illustrative purposes only.
